DESIGN FOR A VALVE HANDLE CAP

Parker B. Francis, Kansas City, Mo.

Application April 30, 1934, Serial No. 51,589

Term of patent 3½ years

To all whom it may concern:

Be it known that I, PARKER B. FRANCIS, a citizen of the United States, residing at Kansas City, in the county of Jackson and State of Missouri have invented a new, original, and ornamental Design for a Valve Handle Cap, of which the following is a specification, reference being had to the accompanying drawing, in which:

Figure 1 is a perspective view of a valve handle cap showing my new design.

Figure 2 is a side elevation of the ornamental valve handle cap shown in Figure 1.

I claim:

The ornamental design for a valve handle cap as shown.

In testimony whereof I affix my signature.

PARKER B. FRANCIS.
